UNITED STATES PATENT OFFICE.

GEORGE B. ALLEN, OF SAN LEANDRO, CALIFORNIA.

BALING-PRESS.

SPECIFICATION forming part of Letters Patent No. 443,172, dated December 23, 1890.

Application filed March 28, 1890. Serial No. 345,749. (No model.)

To all whom it may concern:

Be it known that I, GEORGE BEAMON ALLEN, a citizen of the United States, residing at San Leandro, Alameda county, State of California, have invented an Improvement in Baling-Presses; and I hereby declare the following to be a full, clear, and exact description of the same.

My invention relates to baling-presses; and it consists in the novel constructions, combinations, and arrangements hereinafter fully described, and specifically pointed out in the claims.

The object of my invention is to provide a simple and effective means for operating the followers of the press, for providing for the relief of the power-lever when the pressure on the follower is withdrawn, and for automatically locking and releasing the feed doors of the press.

Referring to the accompanying drawings for a more complete explanation of my invention, Figure 1 is a side elevation of my press. Fig. 2 is a horizontal section of the frame to show the gears and operating-links in plan. Fig. 3 is a top view of the latch mechanism. Fig. 4 is a view of the operating-lever E, shown as having started on its movement to the right, as indicated by the arrow.

30 A is the body of the press, having within it a baling-chamber at each end, provided with suitable discharge-doors a. In these baling-chambers are the oppositely-reciprocating followers B.

35 About the center of the press are mounted the power-gears, (represented generally by C.) These are here shown as being semicircular gears intermeshing horizontally in pairs. They are all mounted in horizontal planes, 40 and there are four of them, two being mounted upon a vertical shaft c and the other two being mounted on a vertical shaft c'. The pair of gears in the same horizontal plane intermesh, as shown. One of the followers—say, for example, the one on the right-hand side—is connected by a link D with the upper gear of one vertical pair and by a link D' with the lower gear of the other vertical pair. The other follower—namely, the one on the left-hand side—is connected by a link D² with the lower gear of the first vertical pair and by a link D³ with the upper gear of the other

vertical pair. These connections are made by the pins d and d' in the rims of the gears, the former pins representing those of the links D and D' and the latter pins representing those of the links D² and D³. All these links are branched or double, so as to fit both above and below the gear-rims. Now it will be seen that by the movement of these gears 60 in one direction the follower on one side is driven outwardly, while the follower on the other side is withdrawn toward the center, and by the movement of the gears in the reverse direction the reverse operation takes 65 place, the first follower being withdrawn and the second driven outwardly.

The first point of advantage to be noticed is that by connecting the followers in such a manner as to have the power imparted to 70 them from each side equally said followers are driven straight and accurately, avoiding any undue friction in the baling-chambers. The object in having four of these gears is to allow the several links to pass each other in 75 accomplishing the full movement of the followers. There is a point of novelty to be noticed of great importance in the relative positions of the pins d and d', by which the power-links are connected with the gears. 80 The pins of the links of both followers are placed to one side of the center planes of the gears. The pins d are on one side and the pins d' are on the other side, their distance from the center planes being equal, and on account 85 of the position and direction of movement of the gears the pins d are placed on the gears nearer their inner ends, while the pins d' are placed toward their outer ends. This construction provides for a much greater stroke 90 of the followers than if said connections were placed directly in the center planes, and also provides for the immediate start of one follower on its outward stroke before the other follower is perceptibly affected to begin its 95 return movement.

The gears are operated by the following mechanism: A power-lever E has its inner end pivoted upon one of the vertical shafts of the gears, here shown as being applied to 100 the shaft c. A link F has one end branched or forked and is connected with one end of the upper gear on shaft c, and a second link F', lying directly under the first, is similarly

- connected with the corresponding end of the lower gear. The rear ends of these links extend to one side of the lever E, and a single pin f passes through said ends, said pin being mounted and adapted to slide back and forth in an elongated guide slot or opening e in the lever. A third link F^2 is similarly connected with the other end of the upper gear, and a fourth link F^3 is similarly connected with the corresponding end of the lower gear. The other ends of these links extend to the lever E and receive a single pin f' , which is mounted and adapted to slide in a longitudinal slot or guide opening e' in said lever.
- 15 Pivoted near the inner end of the lever by a cross-head g is a pawl or catch-bar G, the outer end of which is adapted to bear behind the pin f of the links F and F' , and said pawl has a shoulder g' , which is adapted to bear
- 20 behind the pin f' of the links F^2 and F^3 when said pawl is swung over. A spring H is connected to a fixed bearing at one end and has its other end connected with the pawl or catch-bar, and the tendency of said spring is to
- 25 keep the pawl or catch-bar over to its engagement normally against the pin f . The pawl or catch-bar is swung over to the other side by means of wires or rods I, connected with the ends of its cross-head g , said wires
- 30 or rods extending forwardly along the lever E and connected at their forward ends with the arms of a pivoted bell-crank or elbow lever J, whereby they are adapted to be moved in opposite direction.
- 35 The operation of this mechanism is as follows: In Fig. 2 the lever E is shown as having just completed its movement to the left. Now to begin its movement to the right the pivoted bell-crank or elbow J at the outer end
- 40 of lever E is turned so as to pull upon that rod I, which is farthest from the press. This will turn the pivoted cross-head g of catch-bar G, and will thereby swing said catch-bar over from its position shown in Fig. 2 to the
- 45 position shown in Fig. 4—that is to say, its extreme end is thereby removed from contact with pin f and its shoulder g' is thrown in behind pin f' , and this movement is against the tendency of spring H, which, as before
- 50 stated, acts to hold the catch-bar in the position shown in Fig. 2. Now the lever E is moved on its stroke to the right, as indicated in Fig. 4. In this movement the tendency of pin f' is to slide along toward the pivoted end of lever E—that is, inwardly—and the tendency of pin f is to slide outwardly along the lever. This tendency of pin f is unchecked; but the tendency of f' is checked by its contact with shoulder g' of catch-bar
- 55 G. Therefore the links F^2 F^3 are thereby connected with the lever, and said links, being now pulled upon, turn the gears to the left. The links F F' being free, their pin f , which at first moves outwardly freely, stops when
- 60 the arrest of pin f' takes place. The parts thus remain in the position of Fig. 4 throughout the whole stroke of lever E to the right.

When the limit of this stroke is reached and the power on the lever relieved, the slight expansion of the bale would have a tendency, 70 by throwing the follower back slightly, to turn back the gears slightly, and thereby suddenly jar or vibrate the lever; but this back movement of the gears does not so affect the lever, for the pin f' of links F^2 and F^3 can move 75 freely outwardly away from the catch-bar's shoulder g' , and the pin f of links F F' is not limited at all and can play freely inwardly. To effect the return-stroke of lever E over to the left, the bell-crank J is released, and the 80 spring H throws the catch-bar G over again, so that its shoulder g' is removed from pin f' and its end is thrown behind pin f . Then the movement begins, and when the now-inwardly-sliding pin f comes against the end 85 of the bar G it is stopped, and thereby the links F and F' are connected with the lever E and the gears are turned to the right, the pin f' being now free. The parts remain in this position, as is shown in Fig. 2, until the 90 stroke to the left is completed. The gears C are loose on their shafts, and by reason of the opposite connections of the power-links of the followers one horizontal pair of said gears has always a strain upon it; 95 but the other horizontal pair, being independent on the shafts, can adjust themselves so as to avoid any lost motion in the mesh. In the top of the press are the upwardly-swinging feed-doors K. These are automatically raised by means of a crank-weight W, a rock-shaft w , carrying a lever w' , and a connecting-link w^2 between said lever and the doors. The doors are held down by means of sliding latches L, the ends of which 100 project over the free edges of said doors, and said latches are normally held in a projected position by means of springs l. These latches are alternately withdrawn in order to relieve the doors by the following means: Upon the 105 top of a guide-frame b of each follower is a contact-bar b' . Pivoted in the top of the press at the point m is a swinging lever M, the lower end of which is adapted to be struck alternately by the contact-bars b' of 110 the follower-frames. Over the upper end of this lever is freely looped an open link N, which extends in one direction and is connected with one of the latches. A second open link N' is freely fitted over the top of 115 the lever, and extends in the other direction and is connected with the other latch. Now upon one of the contact-bars coming in contact with the lever said lever is moved in one direction so that it pulls upon one of the 120 open links, but moves freely in the other, and the one it pulls upon withdraws its latch. The same operation takes place with the other latch by contact with the other follower.

Having thus described my invention, what I 130 claim as new, and desire to secure by Letters Patent, is—

1. In a baling-press, the oppositely-reciprocating followers, one in each end of the press,

in combination with the mechanism for operating them, consisting of the horizontal gears mounted in pairs on vertical shafts and intermeshing in horizontal pairs, links connecting one of said followers with a lower gear of one vertical pair and the upper gear of the other vertical pair, links connecting the other follower with the upper gear of the first-named pair and the lower gear of the other pair, and means for operating the gears, substantially as herein described.

2. In a baling-press, the oppositely-reciprocating followers, one in each end of the press, in combination with the four gears C, mounted in vertical pairs and intermeshing in horizontal pairs, the links of one follower connected one with the lower gear of one vertical pair of gears and the other with the upper gear of the other vertical pair, and the links of the other follower, one connected with the upper gear of the first-named pair and the other with the lower gear of the other pair, the points of connection of the first-named links being to one side of the center plane of the gears and the points of connection of the other links being an equal distance on the other side of the center plane of the gears, and means for operating the gears, substantially as herein described.

3. In a baling-press, the intermeshing horizontal gears and connections between said gears and the followers, whereby the latter are operated, in combination with the lever pivoted upon the shaft of one gear, the links connecting the ends of said gear with the lever, the pins at the inner ends of said links mounted and adapted to slide in said lever, and the swinging pawl or catch-bar engaging and controlling the movement of said pins, substantially as herein described.

4. In a baling-press, the intermeshing gears and connections between them and the followers, in combination with the power-lever

mounted upon the shaft of one gear, the links connected with the ends of said gear, the sliding pins connecting the other ends of the links with the lever, the swinging pawl or catch-bar for controlling the movement of the pins, said pawl or bar having a cross-head, and the wires or rods and bell-crank lever for operating the pawl or catch-bar and the spring for controlling it, substantially as herein described.

5. In a baling-press, the oppositely-reciprocating followers in each end of the press, the vertical pairs of gears intermeshing in horizontal pairs, and the power-links D D' D² D³, connecting the followers, respectively, with the upper gear of one vertical pair and the lower gear of the other and the lower gear of the first pair and upper gear of the other, as described, in combination with the power-lever pivoted upon the vertical shaft of one pair of gears, the links connecting the ends of said pair of gears with the lever, the sliding pins of said connection, and the swinging pawl or catch-bar for controlling the movement of the pins, substantially as herein described.

6. In a baling-press, and in combination with its feed-doors and reciprocating followers, the normally-projected latches for holding the doors closed, and the means for withdrawing the latches, consisting of the pivoted lever, the contact-bar on the followers, and the open links connected with the latches and loosely looped from opposite directions over the top of the lever, substantially as herein described.

In witness whereof I have hereunto set my hand.

GEORGE B. ALLEN.
